UNITED STATES PATENT OFFICE

FREDERICK GROVER, OF LEEDS, ENGLAND, ASSIGNOR TO THE FORGROVE MACHINERY COMPANY LIMITED, OF LEEDS, ENGLAND

WRAPPING MACHINE

Application filed August 7, 1931, Serial No. 555,829, and in Great Britain November 7, 1930.

The object of this invention is to wrap cylindrical objects such for instance as sugar sticks made by confectioners, lozenges or coins in column formation, and any such similar articles which on assembly in columns are built up into cylindrical form. In the case of sticks having a right cylindrical form the ends of the stick may be tapered round or flat at either or both ends. Octagonal lozenges and elliptical objects may also be wrapped in the apparatus and for the sake of brevity the sticks and other articles or columns of articles to be wrapped are hereinafter termed "cylindrical objects".

The closing of the ends of the tubular wrapper extending beyond the cylindrical object may be effected by twisting when the wrapper is suitable for such treatment, or by folding by means of folders capable of forming segmental tucks in sequence to cover the ends of the cylindrical object.

One particular purpose of the invention is to enable cylindrical objects to be wrapped with cellophane, which is extremely difficult to handle mechanically owing to the instability of such cellophane when drawn say from a reel into a single layer. The cellophane is extremely sensitive to atmospheric conditions of temperature and humidity which results in unforeseen local distortions. The disturbing effect of these distortions on the wrapping operation must be prevented by the mechanism controlling the cellophane during the processes of drawing the sheet from the reel, cutting it, and wrapping it tightly around the article to be wrapped.

Generally, the invention consists in the combination of two cylindrical formers concentrically arranged and spaced apart, wrapper grippers on said cylindrical formers, means for rotating said formers for winding a wrapper around said formers, and a pocket for supporting between said formers and concentric therewith a cylindrical object to be wrapped in said wrapper, said pocket having an inclined wall whereby the cylindrical object tends to move upwardly free from the pocket when the wrapper is carried around the cylindrical object.

A further feature of the invention consists

in providing means, such as twisting grippers, for gathering in the ends of the wrapper about the ends of the cylindrical object spaced apart from said cylindrical formers and providing means for feeding the pockets to said twist grippers and for holding the wrapper about the cylindrical object while it is fed.

The invention will now be described with reference to the embodiment shown upon the accompanying drawings, wherein:—

Fig. 1 illustrates a longitudinal sectional elevation of a fragment of a wrapping machine for wrapping cylindrical objects in tubular wrappers, according to this invention.

Fig. 2 is a fragmentary sectional view on the line II—II in Fig. 1.

Figure 3 illustrates a part of one of the end grippers drawn to an enlarged scale.

Fig. 4 shows one of the pockets drawn to an enlarged scale and illustrates how the cylindrical object is freed from the walls of the pocket by the action of winding the wrapper around its cylindrical surface.

Fig. 5 illustrates diagrammatically how the cylindrical object is laterally supported.

Figs. 6, 7 and 8 illustrate diagrammatically the cylindrical object and wrapper in three successive stages of the wrapping operation.

Fig. 9 illustrates a modification of the final stage of the wrapping operation.

Figures 10 and 11 illustrate in side and end views respectively one of the twist grippers.

In the example of construction shown upon the accompanying drawings, a chain A is provided which carries a series of open-ended pockets B. The chain has imparted to it a step by step movement by means of the Maltese wheel C fixed on a chain sprocket (not shown), said wheel being actuated by a driving member D in a well-known manner. The cylindrical objects E are placed in the pockets and are carried along by the chain into a number of successive positions. In one of these positions the pocket comes to rest between two round formers F, F¹ of the same or nearly the same diameter as the cylindrical object in the pocket. The formers F, F¹ are

then co-axial with the cylindrical object. Retaining rails or guides G are provided to prevent lateral displacement or the falling out of the pockets of lozenges or discs when the cylindrical object is composed of a number of such lozenges or discs in column formation until the cylindrical object reaches a position co-axial with the formers F, F¹. The rails are discontinued at the position of the formers F, F¹ and the formers are themselves so arranged as to prevent said lateral displacement or falling out of the cylindrical object when this arrives between the formers. Each former is provided with a flat spring clip or gripper H adapted to grip the side of a wrapper adjacent its leading edge against the former. The flat spring clip or gripper H is pivotally mounted at H¹ on a lug F⁴ carried by an extension F² of each former and is provided with an arm H² which extends through a slot in said extension F² and engages in a slot I in the end of a gripper actuating rod I¹. The gripper actuating rod is operated by an arm I² shown in Fig. 2, actuated by a cam or other mechanism (not shown) in the cycle of the machine operation to cause the gripper to open to receive the wrapper, to close the gripper to grip the wrapper during the wrapping operation, and, finally, to open the gripper after the wrapping operation to release the wrapper. When the gripper is stationary, it is located in such a position as to admit the edge of the wrapper J moved forward by feeding mechanism (not shown). The gripper is then closed and in this position the leading edge of the wrapper lies parallel to the axis of the cylindrical object, and the wrapper extends tangentially to the cylindrical object in the direction of length of the wrapper, as shown in Fig. 6, which is the initial position of the wrapping operation. The outer sides of the wrapper adjacent the leading edge will thus be gripped by the grippers so that by simultaneous rotation of the formers, the leading edge will be moved around the cylindrical surface of the object, while the remaining portion of the wrapper will be gradually wrapped around the cylindrical surface of the object against which it will be held by the pocket B. The movement of the leading edge of the wrapper around the cylindrical surface of the object will be facilitated by the object being free to rotate as the winding proceeds.

It might be thought that the central part of the leading edge of the wrapper would crumple when entering between the cylindrical object and the pocket wall. This, however, is obviated by causing the formers F, F¹ after the wrapper has been gripped to separate slightly in an axial direction, which is effected by levers L operated by cam mechanism. By this separation of the formers the leading edge of the wrapper is pulled taut

enough to resist the crumpling effect which might be obtained with an otherwise unstable leading edge. Further precaution is made by so shaping the pockets that in the action of winding on the wrapper, the rotation of the cylindrical object has the effect of freeing rather than wedging it against the walls of the pocket. This is attained by providing the pocket with a wall B¹ which is inclined upwardly and forwardly up which the cylindrical object tends to move from a position shown in dotted lines to a position shown in full lines in Fig. 4, when the wrapper is being moved around its cylindrical surface. Such freeing action is well understood in the construction of silent pawls and the like.

The formers are rotated by means of tooth wheels K fixed thereon and meshing with further tooth wheels K¹ which are driven from the driving mechanism of the machine. The wheel K is wider than the wheel K¹ and is so arranged as to permit of axial movement of the formers. When the formers have been rotated sufficiently to wind on the cylindrical object the required length of wrapper, rotation of the formers will cease and the spring grippers will then be released. The formers and grippers are then withdrawn in an axial direction clear of the tubular ends of the wrapper by means of the lever L which is operated by cam mechanism. Provision may be made for the ingress of air to the spaces vacated by the formers on their withdrawal. In order to prevent lateral displacement of the wrapper in the pocket during withdrawal of the formers, two thin blades G¹ (Fig. 5) are provided in continuation of the rails G, these blades lying one between each end of the cylindrical object and the innermost end of the adjacent former, said blades being of such segmental shape as to impinge against the outer edges of the cylindrical object to prevent lateral displacement thereof, while not interfering with the formation of the tubular wrapper.

It might reasonably be expected that inasmuch as the wrapper is wound around the formers and eventually is wound over the spring grippers, that when the latter are moved outwardly to release their grip, the action of release would either loosen the whole end of the wrapper or alternatively, the spring grippers would tear their way through the tubular ends of the wrapper. This effect is avoided by constructing the cylindrical surface adjacent the ends of the former with a flat portion F³ with which the gripper H is adapted to contact so that the surface where the grippers act is of less diameter than that of the cylindrical surface of the former by which the tubular wrapper is formed. By this artifice the tubular wrapper is tightly wound around the extreme ends of the formers but that portion of the tubular wrapper containing the grippers is of loose spiral

formation, and is therefore capable of easy distortion to give space for the outward movement of the gripper (only a few thousandths of an inch) required to release the gripper.

5 After the wrapping operation has been completed and the formers and grippers have been withdrawn, the wrapper is in the position shown in Fig. 7, which is the final position of the wrapping operation.

10 After the wrapping operation has been completed and the formers withdrawn, the pocket containing the wrapped object passes along the machine between the guide rails G^2 until the wrapper and object are brought 15 in between revolving grippers. These guide rails G^2 are located one at each end of the cylindrical object so as to impinge on the ends of said object, said rails being slotted for the passage of the tubular wrapper ends.

20 Such revolving grippers indicated by N in Figure 1 are shown in Figures 10 and 11 of the accompanying drawings and comprise two flat gripper plates N^1 , N^2 each fixed to one end N^3 of a lever N^4 pivoted at N^5 on a 25 bracket N^6 and carrying at its other end N^7 a bowl N^8 which is held against the periphery of a cam O by the spring N^9 . Two cams O are provided one for each gripper plate, these cams being fixed on an extension O^1 30 of the cam operating gear wheel O^2 meshing with the driving gear wheel O^3 . The bracket N^6 is fixed by a screw N^{10} to a shaft N^{11} which passes through the cam operating gear wheel O^2 and is formed with gear teeth N^{12} 35 meshing with the driving gear wheel N^{13} . The driving gear wheels O^3 and N^{13} drive the gears O^2 , N^{12} in such a timed relationship that the gripper plates N^1 , N^2 are moved together and effect the twisting of the ends 40 of the wrappers before being allowed to be opened by the action of the springs N^9 . The twist grippers are movable endwise to bring the gripper plates N^1 , N^2 when separated against the untwisted projecting wrapper 45 ends and to withdraw them from the twisted wrapper ends by the engagement with the shaft N^{14} on the gear N^{12} of an arm P , actuated by cam mechanism. These twist grippers are rotated in opposite directions to twist 50 the wrapper ends. The gripper plate N^1 is resiliently retained on the end N^3 by the springs N^{15} in order that it may give to accommodate the thickness of wrapper gathered between said plates. Two of these revolving twist grippers are provided, one at 55 each end of the pockets and these twist grippers are adapted to grip the projecting open cylinder ends of the wrapper and are adapted to be rotated in opposite directions in order to twist said ends into the position shown 60 in Fig. 8 which shows the wrapper at the end of a twisting operation. The wrapper in the pocket continues to be carried forward by the chain until it reaches a position at 65 the end of the conveyor where the wrapped

object is precipitated on to an inclined discharge table O , as shown in Fig. 1.

In a modified construction where end folds are required instead of twisted ends, the pockets are brought consecutively opposite 70 folding blades of known construction which act to turn in the ends of the wrapper, as shown in Fig. 9.

What I claim as my invention and desire to secure by Letters Patent is:—

1. A wrapping machine, comprising, in combination, two cylindrical formers concentrically arranged and spaced apart, wrapper grippers on said cylindrical formers, means for rotating said formers for winding a wrapper held by said grippers around said formers, a pocket for supporting between said formers and concentric therewith a cylindrical object to be wrapped in said wrapper, said pocket having an inclined wall 85 whereby the cylindrical object tends to move upwardly free from the pocket when the wrapper is carried around the cylindrical object, means for moving said formers outwardly to withdraw them from the wrapper after the latter has been wound; two oppositely rotatable twist grippers spaced apart from said cylindrical formers for twisting the ends of said wrapper; means for feeding said pocket from a position in 90 which the cylindrical object and its wrapper are between the formers to a position in which they are between the two twist grippers, and means for maintaining the wrapper around the cylindrical object while it is 95 fed from the formers to the twist grippers. 100

2. A wrapping machine, comprising, in combination, two cylindrical formers concentrically arranged and spaced apart, grippers on said cylindrical formers for a wrapper, means for rotating said formers for winding said wrapper around said formers, pockets for supporting between said formers and concentric therewith cylindrical objects to be wrapped in said wrapper, said pockets having an inclined wall whereby the cylindrical object tends to move upwardly free from the pocket when the wrapper is carried around the cylindrical object, means for moving said formers outwardly from each other 115 whereby after being gripped by said grippers the wrapper is pulled taut and after winding the formers are retracted from opposite ends of said wrapper, two oppositely rotatable twist grippers spaced apart from said cylindrical formers for twisting the ends of said wrapper, means for feeding said pockets to the formers, from the formers to the twist grippers and from the twist grippers, and means for maintaining the wrapper around the cylindrical object while it is fed 120 from the formers to the twist grippers. 125

3. A wrapping machine, comprising, in combination, two cylindrical formers concentrically arranged and spaced apart, grip- 130

- pers on said cylindrical formers for a wrapper, means for rotating said formers for winding said wrapper around said formers, pockets for supporting between said formers 5 and concentric therewith cylindrical objects to be wrapped in said wrapper, means for moving said formers outwardly from each other whereby the formers are retracted from opposite ends of said wrapper, means spaced 10 apart from said cylindrical formers for gathering the ends of said wrapper on to the ends of the cylindrical object, means for feeding said pockets from the formers to the twist grippers, and means for maintaining the 15 wrapper around the cylindrical object while it is fed from the formers to the twist grippers.
4. A wrapping machine, comprising, in combination, two cylindrical formers concentrically arranged and spaced apart, grippers 20 on said cylindrical formers for a wrapper, means for rotating said formers for winding said wrapper around said formers, pockets for supporting between said formers 25 and concentric therewith cylindrical objects to be wrapped in said wrapper, said pockets having an inclined wall whereby the cylindrical objects tend to move upwardly free from the pocket when the wrapper is carried 30 around the cylindrical objects, means for moving said formers outwardly from each other whereby after being gripped by said grippers the wrapper is pulled taut and after winding the formers are retracted from opposite 35 ends of said wrapper, two oppositely rotatable twist grippers spaced apart from said cylindrical formers for twisting the ends of said wrapper, a conveyor for said pockets, means for intermittently feeding said pockets to the formers, from the formers to the twist grippers, retaining means for preventing lateral displacement of said cylindrical objects in their movements to the formers and while located 40 between said formers, and means for preventing lateral displacement of said cylindrical objects and for maintaining the wrapper around the cylindrical object while it is fed from the formers to the twist grippers.
5. A wrapping machine, comprising, in combination, two cylindrical formers concentrically arranged and spaced apart, said formers having a flat portion on their cylindrical surface, grippers opposed to the flat portion on said cylindrical formers for gripping a wrapper to said flat portion, means for rotating said formers for winding said wrapper around said formers, an open-ended 55 pocket for supporting between said formers and concentric therewith cylindrical objects to be wrapped in said wrapper, means for moving said formers outwardly from each other whereby after being gripped by said grippers the wrapper is pulled taut and after 60 winding the formers are retracted from opposite ends of said wrapper, two oppositely rotatable twist grippers spaced apart from said cylindrical formers for twisting the ends of said wrapper, means for feeding said pockets to the formers, from the formers to the twist grippers, and means for maintaining the wrapper around the cylindrical object while it is fed from the formers to the twist grippers.
6. A wrapping machine, comprising, in combination, two cylindrical formers concentrically arranged and spaced apart, grippers on said cylindrical formers for a wrapper, means for rotating said formers for winding said wrapper around said formers, pockets for supporting between said formers and concentric therewith cylindrical objects to be wrapped in said wrapper, means for moving said formers outwardly from each other whereby after being gripped by said grippers the wrapper is pulled taut and after winding the formers are retracted from opposite ends of said wrapper, two oppositely rotatable twist grippers spaced apart from said cylindrical formers for twisting the ends of said wrapper, means for feeding said pockets to the formers, from the formers to the twist grippers, and means for maintaining the wrapper around the cylindrical object while it is fed from the formers to the twist grippers.
7. A wrapping machine, comprising, in combination, two cylindrical formers concentrically arranged and spaced apart, grippers on said cylindrical formers for a wrapper, means for rotating said formers for winding said wrapper around said formers, pockets for supporting between said formers and concentric therewith cylindrical objects to be wrapped in said wrapper, means for moving said formers outwardly from each other whereby after being gripped by said grippers the wrapper is pulled taut and after winding the formers are retracted from opposite ends of said wrapper, two oppositely rotatable twist grippers spaced apart from said cylindrical formers for twisting the ends of said wrapper, means for feeding said pockets to the formers, from the formers to the twist grippers, and means for maintaining the wrapper around the cylindrical object while it is fed from the formers to the twist grippers.
8. A wrapping machine, comprising, in combination, two cylindrical formers concentrically arranged and spaced apart, pockets for supporting between said formers and concentric therewith cylindrical objects to be wrapped in said wrapper, said pockets having an inclined wall disposed approximately tangential to the cylindrical formers, grippers on said cylindrical formers adjacent said inclined wall for a wrapper, means for rotating said formers and grippers thereby moving the wrapper down the inclined wall and wrapping it around the formers and cylind-

drical object, means for moving said formers outwardly from each other whereby after being gripped by said grippers the wrapper is pulled taut and after winding the formers 5 are retracted from opposite ends of said wrapper, two oppositely rotatable twist grippers spaced apart from said cylindrical formers for gathering the ends of said wrappers, means for feeding said pockets to the 10 formers, from the formers to the twist grippers and from the twist grippers, and means for maintaining the wrapper around the cylindrical object while it is fed from the formers to the twist grippers.

15 In witness whereof I have hereunto set my hand.

FREDERICK GROVER.
